(57) **CLAIM**

We claim the ornamental design for the snowmobile track lugs, as shown and described.

DESCRIPTION

FIG. 1 is a perspective view of the snowmobile track lugs of our design shown in their ordinary environment, mounted on a snowmobile;

FIG. 2 is a fragmentary perspective view of the snowmobile track lugs of our design;

FIG. 3 is a perspective view further highlighting the snowmobile track lugs of our design shown in FIG. 2;

FIG. 4 is a fragmentary top plan view of the snowmobile track lugs of our design shown in FIG. 2;

FIG. 5 is an elevation view of the snowmobile track lugs of our design shown in FIG. 2;

FIG. 6 is an elevation view of the snowmobile track lugs of our design shown in FIG. 2;

FIG. 7 is an elevation view of the snowmobile track lugs of our design shown in FIG. 2; and,

FIG. 8 is an elevation view of the snowmobile track lugs of our design shown in FIG. 2.

Where included, broken lines showing environment or structure are for illustrative purposes only and form no part of the claimed design. The bottom view of the snowmobile track lugs is not part of the ornamental design claimed and is therefore not shown. The snowmobile track lugs in FIG. 1 are shown in a reduced scale.
